By Fred Valentine, Jr. atty.

UNITED STATES PATENT OFFICE.

WILLIAM S. ATWOOD, OF MONTREAL, QUEBEC, CANADA, has invented a new and useful Improvement in END STIFFENER FOR RAILWAY-CARS.

987,279.

Specification of Letters Patent. Patented Mar. 21, 1911.

Application filed May 17, 1909. Serial No. 496,497.

To all whom it may concern:

Be it known that I, WILLIAM S. ATWOOD, of the city of Montreal, in the Province of Quebec and Dominion of Canada, have invented certain new and useful Improvements in End Stiffeners for Railway-Cars, as fully described and claimed in the following statement.

This invention relates to end stiffeners adapted to be used in the construction of steel cars. In building steel cars of various types it is found very desirable to support the end of the car body against stresses due to shifting of the load, bulging of the sides, and other stresses due to sudden stopping or shunting of the cars.

The object of this invention is to provide an inexpensive and efficient stiffening brace that can preferably be made of pressed steel and that can be secured to the end of the car in such a manner as to support same with great strength and rigidity.

The device consists of a substantially U-shaped steel rib having outwardly extending flanges which are adapted to be secured to the car body. The rib is strengthened at intervals by means of braces formed integral with the webs, and the ends of the rib are bent at right angles to overlap the sides of the car. The strengthening ribs are secured in place in a horizontal plane and hold the end of the car rigid with respect to the sides thereof.

In the drawings which illustrate my invention: Figure 1 is a perspective view of the end of a car showing the strengthening ribs secured in position thereon. Fig. 2 is a perspective view of a strengthening rib detached. Fig. 3 is a perspective view of an alternative form of rib. Fig. 4 is a sectional view on the line 6—7 of Fig. 2. Fig. 5 is a sectional view on the line 8—9 of Fig. 2.

Referring to the drawings, 10 designates a car body showing the strengthening members 11 secured to the ends thereof at a suitable distance apart. The strengthening members, which are substantially U-shaped, consist of a pair of approximately horizontal webs 12 connected by means of the integral flat member 13, at right angles to the webs. A pair of flanges 14 extend outwardly from the webs, forming the base of the rib, said flanges being secured to the car body by means of the rivets 15. The strengthening braces 16, which are formed integral with the rib, are preferably pyrami-

dal in form being pressed outwardly from the webs 12 in such a manner that the base rests upon the flange 14 and gradually tapers toward the connecting member 13. The webs 12 reach the highest point at the center of the rib 17, and gradually taper off toward the ends of the rib.

The flanges 14 are bent at right angles to the strengthening rib at each end to form the end flanges 18, which are adapted to be secured to the side sills of the car to hold the end of said car rigidly with respect to the sides thereof. In Fig. 2 it will be noted that the webs of the rib are tapered down to terminate at the point where the end flanges 18 are bent at right angles to the plane of the strengthening member, the said end flanges 18 being flat upon the outer surface and of the thickness of the flanges 14. In Fig. 3 an alternative form is shown in which the webs are continued around the end flanges 18 and terminate at the outer ends of said flanges, as indicated by the numeral 19.

The strengthening members being positioned horizontally and being riveted to the end of the car, and having the end flanges 18 overlapping the sides and being tied thereto, the rigidity of the end of the car will be greatly increased and the car able to withstand shocks and stresses due to shifting of the load, shunting of the car, or bulging of the sides.

Having thus described my invention, what I claim is:—

1. An end stiffener for cars comprising a U-shaped ribbed member formed of a pair of horizontal webs having a connecting member at right angles thereto, side flanges extending outwardly from the webs, strengthening braces formed integral with the webs, and end flanges bent at right angles to the plane of the stiffening member being positioned horizontally with respect to the end of the car and the end flanges being tied to the sides of the car, substantially as described.

2. A device of the character described comprising a U-shaped ribbed member formed of a pair of horizontal webs connected by an integral flat member, side flanges extending outwardly from said webs, end flanges bent at right angles to the side flanges, pyramidal strengthening braces formed integral with the webs, said device being positioned horizontally with respect to the end of the car and adapted to tie the

end of the car body to the sides thereof, substantially as described.

3. A car body comprising a vertical end member tied to the side members by means of a horizontal strengthening rib comprising a U-shaped member formed of a pair of horizontal webs having integral strengthening braces, and flanges extending outwardly from said webs, said flanges being bent at

the ends at right angles to the plane of the 10 strengthening member, substantially as described.

In witness whereof I have hereunto set my hand in the presence of two witnesses.

WILLIAM S. ATWOOD.
